UNITED STATES PATENT OFFICE.

RICHARD PATTISON, OF NEW YORK, N. Y.

STEAM-INJECTOR.

SPECIFICATION forming part of Letters Patent No. 596,121, dated December 28, 1897.

Application filed April 7, 1897. Serial No. 631,079. (Model.)

To all whom it may concern:

Be it known that I, RICHARD PATTISON, of New York, in the county and State of New York, have invented a new and useful Improvement in Steam-Injectors, of which the following is a specification.

This invention is an improvement in steam-injectors of the "double-jet" or "lifting-and-forcing" type.

10 This invention relates particularly to an improvement in the injector set forth and claimed by me in a pending application which was filed January 19, 1897, Serial No. 619,714, and allowed March 19, 1897.

15 The object of this invention is to provide an injector in which the movement of the operating-valve will permit the escape of any back pressure in the pipe or tube between the injector and the boiler check-valve which 20 may be caused by the leakage of steam from the boiler through the said check-valve or from any other cause. By thus permitting the back pressure to escape as the valve is operated the injector is permitted to operate 25 to lift and force the water perfectly and instantaneously.

A further object of this invention is to so arrange the ports in the valve which controls admission of steam to the lifting and forcing 30 chambers, the overflow, and the escape of the back pressure that the throw of the valve-operating handle will be very short.

35 A practical embodiment of my invention is represented in the accompanying drawings, in which—

Figure 1 represents an outside view of the injector, the valve-operating handle being shown in full lines in the position which it assumes when all the ports are closed and in 40 dotted lines in the three positions which it assumes during its movement—the first when the steam is admitted to the forcing-chamber only by way of the lifting-chamber, communication being established from the forcing-chamber to the overflow-chamber; the second 45 when the escape of back-pressure steam is permitted through the valve to the overflow, communication still being established between the steam-inlet and forcing-chamber 50 by way of the lifting-chamber and the overflow-port in the forcing-chamber closed, and

the third position showing the direct communication of steam to the forcing-chamber and to the lifting-chamber, the back-pressure escape and the overflow-port from the forcing-chamber both being closed. Fig. 2 is an outside view of the reverse side of the injector from that shown in Fig. 1 to show the outlet of the overflow-chamber. Fig. 3 represents a vertical longitudinal central section through the injector, the valve or cock being shown in its closed position. Fig. 4 is a side view of the valve-plug. Fig. 5 represents a detail view showing the position of the valve-plug when steam is admitted to the forcing-chamber only through the lifting-chamber, the overflow-port in the forcing-chamber being shown open to the overflow-chamber. Fig. 6 represents in detail the next position of the valve-plug, in which communication is established through the back-pressure port to the overflow, the overflow-port in the forcing-chamber being closed; and Fig. 7 represents the third position of the valve-plug in detail, in which steam is admitted directly to the forcing-chamber, and directly to the lifting-chamber, the back-pressure port being closed and the overflow-port in the forcing-chamber being closed.

The injector-casing is denoted as a whole 80 by A, its steam-inlet by a, its water-inlet by a', and its discharge opening or outlet by a'', to which discharge-opening may be attached any suitable pipe or tube (not shown) leading to the boiler. The steam-chamber is denoted by B, the lifting-chamber by C, the forcing-chamber by D, and the overflow-chamber by E. The injector-casing is further provided with a suitable valve-seat f, to which is fitted a rotary valve or cock F, 90 having a suitable stem f', to which is attached a suitable operating-handle f'' for turning the said valve. The steam-inlet a is provided with a suitable port a³, opening into the valve-seat f. The steam-chamber B is 95 provided with a suitable port b, opening into the valve-seat f a short distance from the port a³. The overflow-chamber E is provided with a port e, opening into the valve-seat f, and adjacent to the said port is located a suitable overflow-port d, opening from the forcing-chamber D into the valve-seat. A steam-

port d' also opens from the valve-seat f into the forcing-chamber D through the forcing-nozzle, to be hereinafter described.

The lifting-chamber C communicates with 5 the forcing-chamber D through a lifting-tube G, and the steam-chamber B connects with the lifting-chamber C through a steam-nozzle g , which nozzle is located in position to direct the steam into the lifting-tube G for lift- 10 ing the water into the forcing-chamber D. A forcing-tube H is located in the forcing-chamber D, near its outlet or discharge opening a^2 , and a steam-nozzle h is located in position to direct the steam which enters the port d' , 15 when the valve F is "full open," into the forcing-tube H for forcing the water within the chamber D into the boiler. The casing A is also provided with a back-pressure chamber or conduit I, which opens at one end, as 20 at i , into the discharge end of the injector beyond the forcing-chamber D. The other end of the back-pressure chamber I opens into the valve-seat F to form a port i' , which port i' is located between the steam-inlet port a^3 and the steam-port d' . 25

The valve F is provided with a suitable through-port f^3 , which port is considerably larger at one side of the valve and is gradually reduced through to the other side of the 30 same. The valve F is further provided with a suitable through-port f^4 , which extends through the valve F at an angle to the port f^3 , and in the present instance passes through a web f^5 , extending through the through-port 35 f^3 , the said web f^5 being spaced from the bottom and top of the said port f^3 to permit the free passage of the steam above and below the web for permitting the steam to pass from the inlet a^3 , through the port f^3 , into the steam- 40 port d' when the valve is turned to "full open." The through-port f^3 serves also to open communication between the steam-inlet a and the steam-chamber B through the ports a^3 and b . The through-port f^4 serves, when 45 the valve is in one position, to open communication between the forcing-chamber D and the overflow-chamber E through the ports d and e , respectively, and when in another position to open communication between the 50 back-pressure chamber I through its port i' and the overflow-chamber E through its port e . The casing A is provided upon its exterior with stops a^4 a^5 , located in position to be engaged by the operating-handle f^2 for limiting its movements. 55

The operation of my invention is as follows: Supposing that the valve be closed, as shown in Figs. 1 and 3, and it be desired to force the water into the boiler, the valve-operating 60 handle is swung around until the valve is in the position shown in Fig. 5, when the port f^3 will have opened communication between the steam-inlet and the forcing-chamber by way of the lifting-chamber and the port f^4 will 65 have open communication between the forcing-chamber and the overflow-chamber. The steam thus admitted will lift water into the

chamber C and from thence into the chamber D, and when the chamber D has been filled the water will overflow through the 70 chamber E. The movement of the valve-operating handle is continued until the valve is in the position shown in Fig. 6, when the port f^4 will have opened communication between the back-pressure chamber I and the overflow-chamber E, at the same time cutting off the overflow-port d from the forcing-chamber. When the valve is in this position, any pressure of steam which may be within the pipe or tube leading from the outlet end of the injector to the boiler between the injector and the check-valve will be allowed to escape through the overflow-chamber E to the atmosphere, thereby leaving the said tube or pipe in proper condition to receive the water 80 through the forcing-tube H, when the valve is turned to "full open." The valve-operating handle f^2 is then caused to complete its swinging movement, when the valve will be caused to turn into the position shown in Fig. 90 7, in which steam is admitted directly through the through-port f^3 into the forcing-chamber D through the port d' and forcing-nozzle h . 95

In this position the through-port f^3 has cut off communication from the back pressure I to the overflow-chamber E. In the last two above-described positions communication has been continuously maintained from the inlet a through the steam-chamber B and lifting-chamber C. 100

It will thus be seen that the movement of a single operating-valve controls the admission of steam to the lifting-chamber and directly to the forcing-chamber and opens and closes communication between the forcing-chamber and the overflow-chamber and between the back-pressure chamber and the overflow-chamber. It will also be seen that the valve as above constructed is caused to have a very limited movement for controlling 105 the several operations of the injector. 110

It is evident that slight changes might be resorted to in the construction and arrangement of the several parts without departing from the spirit and scope of my invention. 115 Hence I do not wish to limit myself strictly to the structure herein set forth; but

What I claim is—

1. In an injector, the combination with a casing provided with steam and water inlets 120 and an outlet, a forcing-chamber, an overflow-chamber, a back-pressure chamber, of means for opening and closing communication between the steam-inlet and forcing-chamber, between the forcing-chamber and 125 overflow-chamber, and between the back-pressure chamber and overflow-chamber, substantially as set forth.

2. In an injector, the combination with a casing provided with steam and water inlets 130 and an outlet, a lifting-chamber, a forcing-chamber, an overflow-chamber and a back-pressure chamber, of a single valve arranged to open and close communication between

the steam-inlet and the lifting-chamber the steam-inlet and the forcing-chamber, the forcing-chamber and the overflow-chamber and the back-pressure chamber and the overflow-chamber, substantially as set forth.

3. In an injector the combination with a casing provided with steam and water inlets and an outlet, a lifting-chamber, a forcing-chamber, an overflow-chamber and a back-pressure chamber, of a single valve for controlling the admission of steam, adapted by successive movements to firstly open communication between the steam-inlet and lifting-chamber, the forcing-chamber and overflow-chamber; secondly close communication between the forcing-chamber and overflow-chamber and open communication between the back-pressure chamber and overflow-chamber and finally to open communication between the inlet and the forcing-chamber and close communication between the back-pressure chamber and overflow-chamber, substantially as set forth.

4. In an injector the combination with a casing provided with a valve-seat, a steam-inlet opening into the valve-seat, a steam-chamber opening into the valve-seat, a forcing-chamber having an overflow-port and a steam-inlet port both opening into the valve-seat, a lifting-chamber communicating with the steam-chamber and forcing-chamber and a back-pressure chamber opening into the valve-seat, of a rotary valve provided with a through-port for opening communication between the steam-inlet and the steam-chamber and between the steam-inlet and forcing-chamber and provided with a second through-port adapted to open communication between the forcing-chamber and overflow-chamber and between the back-pressure chamber and overflow-chamber, substantially as set forth.

RICHARD PATTISON.
